UNITED STATES PATENT OFFICE.

CHARLES M. HEETER, OF BUTLER, PENNSYLVANIA.

BOTTOM-HOLE PACKER.

No. 909,593.

Specification of Letters Patent.

Patented Jan. 12, 1909.

Application filed January 25, 1907. Serial No. 354,044.

To all whom it may concern:

Be it known that I, CHARLES M. HEETER, a resident of Butler, in the county of Butler and State of Pennsylvania, have invented 5 certain new and useful Improvements in Bottom-Hole Packers, of which the following is a specification.

This invention relates to a packer adapted to be set at the bottom of a hole for packing 10 the bottom of a fully drilled well, also for packing the bottom of a hole which is to be drilled deeper by operating through the packer.

The object of the invention is to provide a 15 packer which when uncollapsed has the rubber annulus located above the shoe or lower end of the packer structure, but which when collapsed forces the rubber downward around the shoe almost if not entirely to the bottom 20 of the hole, the lower extremity of the compressed rubber operating in conjunction with the extremity of the shoe for sustaining the packer and preventing it from settling unduly, a tendency which is greater in some 25 sand or rock formations than in others. A further advantage in having the rubber extended clear to the bottom of the hole when the packer is set is that there is less liability 30 of breaking the packer body in two at the upper end of the shoe than when there is a considerable portion of the body or shoe extended beneath the rubber when the packer is set.

A further feature of the invention is the 35 formation of the lower extremity of the shoe which causes it to obtain a firm seat in formation in which otherwise the packer would tend to settle.

In the accompanying drawings, Figure 1 40 is a vertical sectional view of the packer shown in position at the bottom of a hole before being set, and Fig. 2 is a similar view of the packer when set. Fig. 3 is a sectional view of the lower portion of the set packer, 45 illustrating the same as having settled and formed a seat which prevents further downward movement.

Referring to the drawings, 2 designates 50 the tubular packer body having secured to its lower end the tubular shoe 3, formed of thicker metal than body 2, the shoe adjacent its lower end having the annular bulge or enlargement 4. From this enlargement the outer face of the shoe is coned or beveled inward to its lower extremity, as indicated at 55 5. The upper extremity of the shoe is

tapered at 6, so that the rubber annulus 7, surrounding body 2, may readily start downward over shoe 3 when the packer is collapsed.

The upper end of body 2 is enlarged annularly at 8, and loosely fitting around the body beneath the shoulder formed by this enlargement is ring 9, having its under face beveled and bearing against the upper extremity of annulus 7. Ring 9 is secured to the lower extremity of outer or telescoping tubular section 10, and carried by the upper end of the latter is collar 11 to which the tubing or other packer-lowering device is secured.

The telescoping parts of the packer are rigidly united by frangible rivets 12 which extend through tube 10 and enlargement 8 and hold the parts separated or uncollapsed 75 while the packer is being lowered into the well. As soon however as shoe 3 reaches the bottom of the hole and provides the necessary resistance, the weight of the tubing or other lowering device operates to shear 80 rivets 12, whereupon said weight is exerted on the rubber, forcing it downward over shoe 3, which in turn spreads the rubber laterally and forces it tightly against the well wall, as shown in Fig. 2. Thus the 85 shoe of thicker metal performs the double function of supporting the packer and spreading the rubber. The compression of the rubber may be such as to carry it downward no further than enlargement 4, or it 90

may be forced down completely around the latter as far as the lower extremity of shoe 3. The outer taper or bevel 5 of the lower extremity of the shoe wedges into formations which tend to give under the weight of the 95 packer, crowding the sand or rock outward in such a way as to prevent any considerable settling, as will be seen by referring to Fig. 3. This tendency is probably greater when the drilling is continued through and below 100 the packer, also as illustrated in Fig. 3. The packer body or shoe may settle to such an extent as to bring the lower end of the compressed rubber into engagement with the bottom of the hole or with the shoulder in 105 the well upon which the packer rests, as the case may be, and in either event it resists, or at least retards further downward movement. With the rubber extending to the bottom of the hole, there is no appreciable length of shoe or tubing beneath the packed rubber, and hence there is less tend-

ency of the shoe collapsing under the weight of the tubing, or of the shoe being broken by the drilling tools operating therethrough, than in those constructions of bottom hole packers wherein the rubber when compressed or packed terminates a distance upward from the bottom of the hole.

I claim:—

1. A bottom hole packer comprising telescoping inner and outer sections, a shoe secured to the lower end of the inner section and adapted to rest on the bottom of the hole and sustain the packer, and a rubber annulus embracing the said inner section and adapted to be forced downward around the shoe by the said outer section.
2. A bottom hole packer comprising telescoping inner and outer sections, a shoe secured to the lower end of the inner section and adapted to rest on the bottom of the hole and sustain the packer, the shoe being larger externally than the inner section and at its upper end tapered upwardly, and a rubber annulus surrounding the said inner section and adapted to be forced downwardly by the said outer section over the tapered upper end of the shoe and downward around the latter, thereby expanding the annulus radially and contracting it longitudinally.
3. A bottom hole packer comprising telescoping inner and outer sections, a shoe secured to the lower end of the inner section and adapted to rest on the bottom of the hole, the shoe being larger externally than the said inner section and at its upper end tapered upwardly, the shoe having an external enlargement adjacent its lower end, and a rubber annulus embracing the said inner section and adapted to be forced by the said outer section downwardly over the

shoe and over and around the said shoe enlargement.

4. A bottom hole packer comprising telescoping inner and outer sections, a shoe secured to the said inner section and adapted to rest on the bottom of the hole, the shoe being larger externally than the inner section and having its lower extremity tapered for the purpose described, and a rubber annulus surrounding the said inner section and adapted to be forced by the said outer section downwardly over the shoe.

5. A bottom hole packer comprising telescoping sections, a shoe thicker than the inner section and forming a bottom continuation thereof, the shoe having an annular enlargement adjacent its lower end with the outer surface of the shoe coned or beveled from said enlargement to the bottom extremity of the shoe, and a rubber annulus surrounding the inner section of the body and adapted to be forced downward over the shoe when the packer is collapsed.

6. A bottom hole packer comprising a tubular body portion having an enlarged shoulder-forming upper end, a shoe depending from the lower end of the body, a rubber annulus surrounding the body, a ring encircling the body between the upper end of the annulus and said body enlargement, a tubular part secured to and extending upward from the ring and adapted to telescope the body, and frangible rivets uniting said tubular part with the upper portion of the body.

In testimony whereof I affix my signature in presence of two witnesses.

CHARLES M. HEETER.
